(57) **CLAIM**

The ornamental design for a sensing module, as shown and described.

DESCRIPTION

FIG. 1 is a top front perspective view of a sensing module according to some embodiments of the present invention; FIG. 2 is a bottom front perspective view of the sensing module shown in FIG. 1;

FIG. 3 is a front view of the sensing module shown in FIG. 1; FIG. 4 is a back view of the sensing module shown in FIG. 1; FIG. 5 is a top view of the sensing module shown in FIG. 1; FIG. 6 is a bottom view of the sensing module shown in FIG. 1;

FIG. 7 is a side view of the sensing module shown in FIG. 1; and,

FIG. 8 is a corresponding view of the sensing module shown in FIG. 7.
